APPARATUS FOR TREATING OIL

Theodore A. La Brecque, Elmira, N. Y., assignor
to The Hilliard Corporation, Elmira, N. Y., a
corporation of New York

Application July 10, 1934, Serial No. 734,500

6 Claims. (Cl. 196—16)

This invention relates to a structurally and functionally improved reclaiming apparatus, capable of use in numerous different associations, but primarily intended for employment in connection with the reclaiming of oil. The invention additionally contemplates the teaching of a method by means of which oil and similar material may be efficiently and economically reclaimed.

10. It is a well appreciated fact that considerable difficulty has heretofore been encountered in the reclaiming of oil and similar substances. More especially oil—sometimes after only a short and not excessive period of use—has become discolored, diluted with water, gasoline and other liquids, filled with particles of foreign matter, etc. Insofar as the oil itself is concerned, it has, in fact, better body and lubricating characteristics than initially existed, but its usefulness, due 20 to the impurities and discoloration, has been destroyed and it has largely been thrown away.

In certain instances where large amounts of this oil were available, involved processes and apparatus have been resorted to for the reclaiming of the oil. The practice of these processes has been, at best, quite expensive and certain of them have been of doubtful efficiency. In any event, in almost all instances where only small quantities of oil have been in question (in 30 the case of a single service station, or similar plant) it has been entirely uneconomic to attempt a proper reclaiming of the oil and hence most conscientious operators have disposed of the same in any convenient manner.

35. With the foregoing in mind the present invention aims to provide a unitary apparatus comprising relatively few components, each individually simple and rugged in construction, which components, when assembled, provide an oil reclaiming mechanism capable of use over long periods of time with freedom from difficulties.

Moreover, by means of the present invention a setup of apparatus is furnished which will allow of the ready practice of the improved 40 method herein involved.

45. Among further objects of the invention are those of teaching a method and furnishing an apparatus which may be employed by relatively unskilled operators, which may be of a continuous nature, and which will be extremely economical, aside from the fact that the reclaimed product will be of excellent quality and free from discoloration, impurities and dilutents.

With these and other objects in mind, reference is had to the attached sheets of draw-

ings illustrating one practical embodiment of the novel apparatus by means of which the present invention may be practiced and in which drawings

Fig. 1 is a somewhat diagrammatic and partially sectional side view of a grouping of apparatus;

Fig. 2 is an enlarged sectional side view of one unit of such apparatus, and

Fig. 3 is a plan view of certain of the parts 10 shown in Fig. 2.

Referring especially to Fig. 1, numeral 5 indicates a tank of proper capacity and which receives the body of dirty oil. Extending from this tank is a conduit 6 which is connected with 15 a pump 7 for forcing the oil upwardly through the tube 8. The tube may have its body formed to provide a coil 9 for a purpose hereinafter described, and this tube is extended, as at 10, to connect with a head 11 forming a part of a 20 filter casing. The lower edges of the head are drawn towards the base 12 of the filter, as, for example, by means of bolts, nuts and lugs indicated at 13, and a substantially air-tight fit is provided. The continued portion of the tube 25 10 may be of somewhat flexible material, so that the cover 11 may be shifted upwardly without danger of the parts rupturing. Such upward shifting may be conveniently provided for, as, for example, by a lever 14, pivotally connected 30 to a stem 15 affixed to the cover 11 and having its inner end similarly secured to a frame 16 supporting the apparatus. The base 12 is provided with an opening 17, through which the fluid may flow into a vaporizing chamber pro- 35 vided by a casing 18.

As has been particularly shown in Figs. 2 and 3, the base of this vaporizing chamber is preferably formed by employing a conical member 19 which has upon its upper surface a series of 40 annular flanges 20, each interrupted at one end at a point short of a transversely extending baffle 21. In this manner a tortuous passage is provided extending from the central portion of the member 19 and in line with the opening 17 45 to a point adjacent the outer edge of this member at which point an outlet opening 22 is provided. Accordingly, oil flowing through the opening 17 will be deposited centrally of the member and will continue down the tortuous pas- 50 sage, finally flowing through the outlet 22. This outlet connects with a pipe 23 in turn connected to a tank 24 for the purpose of receiving the reclaimed fluid.

Also mounted upon the frame 16 is a motor 55

driven vacuum pump, generally indicated at 25, and which has an outlet 26. The latter should exhaust at a point substantially remote from the operator, so that no objections may be encountered in connection with fumes discharged therefrom. Of course, any other suitable expedient for dissipating these fumes may be resorted to. The suction end of this pump is connected to a tube 27 which, in turn, connects with a tank 28. Extending from this tank is a condenser 29 which may take the form of a downwardly projecting coil, the upper end of which is connected to the vaporizer chamber 18.

Disposed below the member 19 is a heater 29' preferably of the electric type, and a thermostat 30 may be provided at this point for maintaining the temperature of the entire vaporizing chamber substantially constant. At this time it will be noted that the coil 9 heretofore diagrammatically shown in Fig. 1 preferably passes through the chamber within which the heater 29' is disposed. In this manner the oil is properly preheated and flows freely. It will be observed, with reference to the filter, that there may be disposed within the casing of this unit, a shell 31, at the base of which there is arranged a layer of filter paper or equivalent material 32, in turn resting upon a layer of canvas 33 which may be mounted by a ring 34 extending beyond the casing. The outlet opening 17 may be guarded by a screen 35, as shown.

In using an apparatus of this nature, the tank 5 may be of sufficient capacity so that oil may be deposited therein from time to time and allowed to accumulate. After a certain body of oil has so accumulated, the apparatus may be operated. Of course, a certain amount of foreign material may be initially drawn off after the oil has settled, by opening the pet-cock at the bottom of the tank. This tank may have its intake opening guarded by a screen so that large particles or bodies of foreign matter may not be introduced. The heater 29', together with the pumps, is caused to operate, and by the time the fluid reaches the vaporizing chamber the temperature of the latter will have been raised to a proper point. The pump 7 serves to control the flow of oil to be cleaned so that a constant flow is assured even if different viscosities are encountered.

The vacuum pump 25, of course, serves through tube 27, tank 28, tube 29, casing 18, the filter casing, tube 10, and coil 9 to exert a certain suction on the oil flowing upwardly through tube 8, but in most instances it is preferred (as afore brought out) to supplement this action by the pump 7. In any event, the oil passes through the preheating coil 9, so that from this point on it will run freely and is discharged from the end 60 of tube 10 into the filter casing. Disposed within this filter casing is any suitable filtering material as, for example, fuller's earth, or diatomaceous earth, within which a layer of filtering paper or its equivalent may be embedded (not shown). The casing 31 serves to confine this filtering body, and the oil in its passage therethrough obviously flows in intimate contact with particles of the filtering body. In so doing it will be decolorized and cleared, in addition to the fact that any acids 70 present will be neutralized. Moreover, it will be apparent that solids and colloidal impurities will be separated from the oil. The liquid will now flow through the opening 17 into the central space defined by the innermost flange of the conical member 19. In such space, in its subsequent

travel through the tortuous passage, the oil will be subjected to a temperature of approximately 380° F. (the thermostat serving to maintain this temperature).

Due to the flange structure a relatively long 5 passage is provided within the existing constricted space and the inclination of the surfaces should be sufficiently small so that a rapid flow does not occur. The vaporizing chamber being connected to the end of coil 29, of course is subjected 10 to a constant and relatively high vacuum (for example, 20"). As a consequence, the boiling off of water, gasoline, etc., is materially accelerated, in addition to the fact that the resultant vapors are caused to flow into the coil 29. The oil, however, flows through the opening 22 into the tank 15 24 where it may be withdrawn as desired.

The vapors flowing into coil 29 are, of course, condensed and are deposited within the tank 28. From this tank they may be periodically withdrawn 20 as useful by-products, or may be thrown away, as desired. It is obvious that any vapors which have not been recondensed will be harmlessly discharged through the pipe 26, or, if desired, some expedient may be resorted to for the 25 purpose of recapturing them in useful form.

The reclaimed oil will be found to be perfect in every respect, and it is apparent that an apparatus of this nature involves a process which may be practiced by a relatively unskilled person, aside from the fact that the apparatus will 30 operate efficiently in the hands of that person. Moreover, the device may be manufactured in sizes proper for a small user, so that two or three service stations, or even one, may economically 35 employ the apparatus.

It will, of course, be desirable—conditioned upon the amount of use to which the apparatus is subjected—to periodically renew the body of filtering material. This may be achieved readily 40 by simply loosening the coupling structure 13, raising the cover 11, and removing as a unit the shell 31 and the layers 32 and 33. The former should be renewed frequently and the latter may be periodically cleaned so that its term of usefulness 45 may be relatively extended. Of course, some renewal of the canvas layer will have to be resorted to, and also when the filter is open the screen 35 and other parts may be cleaned.

In conclusion, it will be appreciated that in 50 lieu of having the body of filtering material within the filter casing, the earth might be directly deposited in, and agitated within, the tank 5. Also, even if the latter expedient is resorted to, a body of filtering material as afore described 55 might be additionally placed in the filter casing. In all instances, however, it is preferred that pipe 6, as shown, connect with the tank 5 at a point above the bottom of the latter so that, insofar as practicable, materials foreign to the oil will 60 not pass through the system.

Thus, among others, the several objects of the invention as specifically afore noted are achieved. It will be appreciated that the steps of the method might be varied in numerous respects and 65 that the structure of the apparatus might be greatly changed from the illustrated embodiment heretofore referred to, without departing from the spirit of the invention as defined by the claims.

Having described my invention, what I claim as new and desire to secure by Letters Patent is:

1. A purifying apparatus including, in combination, a receptacle to contain oil to be purified, a tube extending from said receptacle and 75

connected thereto, a heating coil connected to said tube, a filter body beyond said heating coil and to which the outlet end of the latter is connected, said filter body being formed with an 5 opening for the passage of cleansed oil, means providing a vaporizing chamber below said filter body, such opening extending through to said chamber, heating means acting within said chamber, suction means, a distillate receiving 10 tank connected to said means, a condenser coil extending from said chamber downwardly to said tank, and a receptacle for reclaimed oil also connected to said chamber.

2. Apparatus for treating oil including a heater 15 having substantially flat heating surface for the travel of oil to be heated and having a seat extending circumferentially of said heating surface, a sheet of filtering material having its periphery supported on said sheet and covering the 20 heater, a clamping member cooperating with said sheet to sealingly clamp the sheet of filtering material and to form a filtering receptacle above said seat, means for passing an oil mixture into said filtering receptacle, and means for 25 creating a pressure differential on the respective sides of said sheet of filtering material to promote flow of oil from the filtering receptacle to the heater.

3. Apparatus for treating oil including a heater 30 having a substantially spiral passageway for passing oil to be heated and having a seat extending circumferentially of said passageway, a sheet of filtering material having its periphery supported on said seat and in covering relation 35 with respect to the heater, a clamping member cooperating with said seat to sealingly engage the sheet of filtering material and to form a filtering receptacle above said seat means for passing an oil mixture into said filtering receptacle, and means for 40 creating a pressure differential on the respective sides of said sheet of filtering material to promote flow of oil through the sheet of filtering material and through said spiral passageway.

45 4. Apparatus for treating oil including a heat-

er having a substantially flat heating surface for the travel of oil to be heated and having a seat extending circumferentially of said heating surface, a sheet of filtering material having its periphery supported on said seat and covering the 5 heater, a clamping member having an annular portion cooperating with said seat to sealingly clamp the sheet of filtering material and to form a filtering receptacle above said seat, means for passing an oil mixture into said filtering receptacle, and means for creating a pressure differential on the respective sides of said sheet of filtering material to promote flow of oil from the filtering receptacle to the heater. 10

5. Apparatus for treating oil including a heater 15 having a substantially spiral passageway for passing oil to be heated and having a seat extending circumferentially of said passageway, a sheet of filtering material having its periphery supported on said seat and in covering relation 20 with respect to the heater, a clamping member having an annular portion cooperating with said seat to sealingly engage the sheet of filtering material and to form a filtering receptacle above said seat, means for passing an oil mixture into 25 said filtering receptacle, and means for creating a pressure differential on the respective sides of said sheet of filtering material to promote flow of oil through the sheet of filtering material and through said spiral passageway. 30

6. Apparatus for treating oil including a heater 35 having a substantially spiral passageway for passing oil to be heated and having a seat extending circumferentially of said passageway, a sheet of filtering material having its periphery supported on said seat and in covering relation with respect to the heater, a clamping member having an annular portion cooperating with said seat to sealingly engage the sheet of filtering material and to form a filtering receptacle above 40 said seat, and means for passing an oil mixture into said filtering receptacle for flow through the sheet of filtering material and through the spiral passageway of the heater. 45

THEODORE A. LA BRECQUE. 45
